UNITED STATES PATENT OFFICE.

SIGMUND ROSENBLÜH, OF NEW YORK, N. Y.

DESIGN FOR SHELF-PAPER.

SPECIFICATION forming part of **Design No. 17,840, dated October 25, 1887.**

Application filed September 14, 1887. Serial No. 249,725. Term of patent 7 years.

To all whom it may concern:

Be it known that I, SIGMUND ROSENBLÜH, of the city, county, and State of New York, have invented a certain new and original Design for Shelf-Paper, of which the following is a specification, reference being had to the accompanying drawing, in which a face view of my new design for shelf-paper is shown.

A is the heading.

10 B are oval panels filled alternately with a leaf-ornament, C, and diamond grating or lattice-work D.

15 E are circular panels between the oval panels, said circular panels containing radial ornaments.

F are arches above the oval panels, and G scallops at the bottom edge of the paper. The remaining part or body of the design, between

the heading and the bottom edge scallops, consists of diamond grating, netting, or lattice-work.

Having thus described my design, I claim as new and desire to secure by Letters Patent—

The design for shelf-paper, substantially as herein shown, the same consisting of a heading, latticed body, alternating oval and circular panels in the lattice body, ornaments in the oval panels, and arches extending over the oval panels, as set forth.

In testimony that I claim the foregoing as my invention I have signed my name in presence of two subscribing witnesses.

SIGMUND ROSENBLÜH.
